UNITED STATES PATENT OFFICE.

ELMORE WILLIAM MENNINGER, OF LOS ANGELES, CALIFORNIA.

REENFORCEMENT FOUNDATION.

Application filed May 8, 1923. Serial No. 637,536.

This invention relates to reenforcement foundations of the type employed by the building trades and in the structural arts where a slab of cementitious material is formed with reenforcing members therein to aid in holding said material in place and to increase the strength of the slab.

An object of the invention is to avoid deterioration in stucco and plaster structures employing a reenforcement foundation which is erected in place and the plaster or stucco then applied thereto, as is customary, for example, in the construction of, so termed, wood-studded stucco and plaster buildings.

Where it is necessary to attach the reenforcement foundation to a frame work as for example, in the construction of a building it has been impossible by prior known constructions to embed all of the reenforcement members in the cementitious material and at the same time avoid large areas of metallic contact of the reenforcement members with the furring at the points of attachment of the reenforcement members with the frame work, said areas readily inducing a breaking down of the slab.

Another object of this invention is to provide for entirely embedding or incasing the oxidizable metal members of the reenforcement foundation within the cementitious slab and at the same time to make provision for effectively securing such members to the structural surfaces of the building or other construction, without in the least subjecting the slab to deterioration promoting bulging and cracking thereof. For example, when the reenforcement foundation breaks because of oxidation of the metal members and becomes detached from the building frame, there are induced bulging and cracking of the stucco or plaster. This invention avoids such bulging and cracking.

Another object is to make provision for increasing the ease of attachment of the reenforcement foundation to its support.

The accompanying drawings illustrate the invention:

Figure 1 is a fragmental view of a reenforcement foundation embodying the invention, staples and fragments of the backing and the plaster or stucco, in which the foundation is embedded, also being shown.

Fig. 2 is a sectional elevation on the line indicated by 2-2, Figure 1.

Fig. 3 is an enlarged fragmental section on the line indicated by 3-3, Figure 1.

Fig. 4 is a fragmental view of a slight modification of the invention.

Fig. 5 is a fragmental perspective view of a modified form of the furring member.

Fig. 6 is a fragmental perspective view of another modification of the furring member, a fragment of a member engaged by the furring being indicated in broken lines.

Fig. 7 is a fragmental side elevation of another form of furring member, fragments of the back and the support, to which the furring member is attached, being shown in section.

Fig. 8 is a fragmental perspective view of a still different modification of the furring member.

Fig. 9 is a longitudinal view of a modified form of the locking member.

Fig. 10 is a longitudinal view of a still different form of the locking member.

Referring first to Figures 1, 2 and 3 of the drawings, there is provided a reticulated member 11 of any suitable construction. In the instance shown the member 11 is formed of crossed rods or wires 12 welded or otherwise secured to one another at their crossing points. The member 11 may be made of oxidizable metal since it is to be perfectly embedded in the plaster or stucco slab, which is indicated at a. Thus the reticulated member 11 will be of comparatively inexpensive construction.

The member 11 is connected with a suitable support, such as that indicated at b, by employing furring members, only one of which is indicated at 13 and which is secured at suitable intervals to the support b by suitable fasteners 14, as, for example, staples. The furring member 13 extends along one side of the reticulated member 11 and not only aids in connecting the member 11 to the support, as will be made clear hereinafter, but it also properly spaces the member 11 from the support so that, when the plaster or stucco is being applied, said plaster or stucco will flow entirely around the reticulated member 11 and completely embed said member. In order that the furring member 13 will properly space the reticulated member 11 from the support, said furring member is provided at intervals therealong with projections 15, preferably in the form of bows, for engagement

by the fasteners 14. The projections 15 extend away from the reticulated member. As shown in Figure 3, both legs of the bows shown at 15 are preferably in the form of 5 compound curves to provide a narrower portion 16 and a wider portion 17, the narrower portion closely fitting the fastener 14 and the wider portion admitting of the head of the hammer used in driving the fastener. 10 The furring member 13 may be connected to the reticulated member 11 at intervals in any suitable manner. In this instance the connection preferably provides for attachment of the reticulated member to the furring member after the furring member has 15 been fastened to the support. In this particular instance the furring member is provided at suitable intervals with outwardly projecting bows, only one of which is shown 20 at 18, in the drawings, projecting through one of the spaces of the reticulated member 11 from the side on which the furring member is positioned to the other side. Through the bow 18 extends a locking member 19 in 25 the form of a pin. The end portions of the pin are interlocked with the member 11. Though said pin may be straight, it is preferably notched or toothed, as indicated at 20, one of the notches at the intermediate 30 portion of the pin engaging the bow 18 and other notches near the ends of the pin engaging two of the wires of the reticulated member 11. Such construction of the pin prevents it from slipping out of place before the plaster or stucco is applied. 35

It will be readily understood that, if the mesh of the reticulated member be sufficiently small, a backing will not be necessary to prevent the plaster or stucco from falling 40 out of place when it is applied, but a backing, such as that indicated at 21, may be employed and, indeed, is essential if the mesh is comparatively large.

To use the invention above described, the 45 backing 21 which may be made of paper or other suitable material, will first be secured to the support *b* and to other like supports, not shown, of the building or other structure in any suitable manner, if said backing 50 is to be employed. The furring members will be secured to the supports upon the backing if such backing be used. After the furring members have been secured in place, the reticulated member will then be laid 55 against the furring members which, accordingly, properly space the reticulated member from the backing. Then the locking pins 19 will be interwoven with the reticulated and furring members into place to connect the reticulated member to the furring members. When these operations have been completed, the plaster or stucco, indicated at 60 *a*, may be applied by any approved method so as to completely embed the reticulated member within the stucco or plaster. 65

Preferably the furring members will be constructed of metal that is practically non-oxidizable, so that they will not rust at the portions of the members 15 that project outside of the stucco or plaster and thus, in time, become detached from the support. The fasteners 14 also will be preferably of non-oxidizable metal. 70

Now referring more particularly to Figure 4, there is illustrated a reticulated member 22 of different construction than the member 11 being, in fact, what is generally termed "expanded metal" or "metal lath". The furring member 13 is the one previously described, but the locking pin 23 is straight, 75 in this instance, with the exception of an angularly bent end 24 which engages the member 22 and, consequently, prevents the locking pin from falling out of place. 80

Now, referring to Figure 5 of the drawings, a furring member is indicated at 25 and is in the form of a metal strip provided with projections or bows 26 at intervals, and the bows are perforated at 27 for securing by nails, not shown, to a support, 90 not shown. The furring member is preferably provided at suitable intervals with other bows, only one of which is indicated at 28, projecting in a direction opposite to the bows 26. The bow 28 corresponds to the 95 bow 18 and is for the purpose of engaging the locking pin, not shown in this view.

In Figure 6 is illustrated a furring member, similar to Figure 5 in some respects, and the same reference characters are employed 100 with the addition of a prime mark to indicate similar features of construction. In this instance, instead of providing the bow 28 to engage the member, indicated in broken lines at 29, the furring member is provided with a tongue 30 which is partially cut and bent from the body of the furring member so as to extend part way around the reticulated member 29. 105

In the form of furring member disclosed 110 at 31 in Figure 7, said furring member is provided at intervals therealong with bows, only one of which is shown at 32. Projecting from the bow 32 is a fastening member 33 formed by pinching together a portion of the furring member so as to form a more or less sharpened member that may be driven into the support, indicated at 34. The backing, indicated at 35, may be employed or not, according to the size of mesh of the reticulated member and desires of the constructor. 115

In Figure 8 is illustrated a still different form of furring member 36 in the form of a strip provided at suitable intervals with bows, only one of which is shown at 37. Projecting from the bow 37 is a fastening member 38 which is formed by pinching together different portions of the strip 36 so as to produce a more or less sharpened member that may be driven into a support. In 120 125 130

making the furring member 36, a strip of metal may be provided with longitudinally extending slits, one of which is comparatively short adjacent the end of the strip, and the other comparatively long beginning a short distance from the first slit. Then the end portion with the shorter slit will be bent at an angle to the remaining portion of the strip and the almost severed portions on opposite sides of the longer slit will be spread edgewise from one another so as to bring them into the positions shown in Figure 8, the two portions being connected by the unslit portion 39.

15 In Figure 9 is shown a locking pin 40 of slightly different construction than the locking pins 19 and 23. The pin 40 has hook-shaped ends 41 adapted to engage the reticulated member, not shown, so as to prevent the pin becoming displaced.

20 In Figure 10 the locking pin 42 is straight with the exception of its intermediate portion which is notched or bowed at 43 similar to the notch 20 of the pin 19 that engages the furring member 13.

25 I claim:

1. A reenforcement foundation comprising a reticulated member, a separate furring member extending along one side of the reticulated member having projections at intervals extending away from the reticulated member to space the reticulated member from the support to which it is to be connected, means for fastening the projections to the support, the furring member having a member projecting through one of the spaces of the reticulated member to the other side thereof, and means removably locking the reticulated member to the furring member.

2. A reenforcement foundation comprising a reticulated member, a separate furring member extending along and having one side engaging one side of the reticulated member at intervals, the furring member having projections at intervals extending away from the reticulated member to space the reticulated member from the support to which it is to be connected, means for fastening the projections to the support, and a locking pin engaging the opposite side of the reticulated member and engaging the opposite side of the furring member.

3. A reenforcement foundation comprising a reticulated member, a separate furring

55 member extending along one side of the reticulated member having projections at intervals extending away from the reticulated member from the support to which it is to be connected, means for fastening the projections to the support, the furring member having a bow projecting through one of the spaces of the reticulated member to the other side thereof, and a locking pin having its intermediate portion extending through the bow and its end portions interlocked with the reticulated member.

4. A reenforcement foundation comprising a furring member having bent portions at intervals to space it from a support and having relatively long straight portions between the bent portions, means to secure the bent portions to the support, a reticulated member separate from the furring member lying against the straight portions of the furring member, the furring member being between the reticulated member and the support, and locking pins at intervals along the furring member between the securing means of the furring member, said locking pins being interwoven with the furring member and reticulated member so as to support the reticulated member.

5. A reenforcement foundation comprising a reticulated member, a furring member having relatively long portions lying in a plane that is parallel to the reticulated member and having other portions extending away from the reticulated member to space the reticulated member from the support to which it is to be connected, means for fastening the furring member to the support, and a pin removably locking the reticulated member to the furring member.

6. A reenforcement foundation comprising a reticulated member, a furring member provided with means at intervals to space it from the support to which it is to be attached, the portion between said means being relatively long and standing in a plane spaced from the support and parallel with the reticulated member, said portion having a projection extending through the reticulated member, and means removably holding the reticulated member against said portion.

Signed at Los Angeles, California, this 26th day of April, 1923.

ELMORE WILLIAM MENNINGER.
